(57) CLAIM

The ornamental design for vehicle-wheel front face, as shown and described.

DESCRIPTION

FIG. 1 is a perspective view of a vehicle front face according to my new design;

FIG. 2 is a front elevational view thereof; and,

FIG. 3 is a side elevational view thereof.

The broken line showing of the five bolt holes and the side of the wheel is included for the purpose of illustrating environment and forms no part of the claimed design.

1 Claim, 3 Drawing Sheets

FIG. 3
